CLAIM

The ornamental design for a case for storing small items, as shown and described.

DESCRIPTION

FIG. 1 is a left front perspective view of a case for storing small items showing a first variant our design;

FIG. 2 is a top plan view of the case for storing small items of FIG. 1;

FIG. 3 is a left side perspective view of the case for storing small items of FIG. 1;

FIG. 4 is an expanded or exploded view of the case for storing small items of FIG. 1;

FIG. 5 is a left front perspective view of a case for storing small items showing a second variant our design;

FIG. 6 is a top plan view of the case for storing small items of FIG. 5;

FIG. 7 is a left side perspective view of the case for storing small items of FIG. 5; and,

FIG. 8 is an expanded or exploded view of the case for storing small items of FIG. 5.

The broken lines showing portions of modules of the case for storing small items are included for the purpose of illustrating portions of the article and form no part of the claimed design.

(Continued)

The undisclosed rear, right and bottom views are unclaimed subject matter.

1 Claim, 4 Drawing Sheets
